F. R. L. *INVENTOR.*
Berge,

BY
Geo. P. Kimmel.
ATTORNEY.

UNITED STATES PATENT OFFICE.

FRANS R. L. BERGE, OF SEATTLE, WASHINGTON.

RESONATOR ATTACHMENT FOR BANJOS AND THE LIKE.

Application filed June 21, 1924. Serial No. 721,560.

To all whom it may concern:

Be it known that I, FRANS R. L. BERGE, a citizen of the United States, residing at Seattle, in the county of King and State of

5 Washington, have invented certain new and useful Improvements in Resonator Attachments for Banjos and the like, of which the following is a specification.

This invention relates to a resonator attachment for banjos and the like and is 10 designed primarily as an improvement upon the form of resonator disclosed in Letters Patent #1,461,596, granted to me July 10, 1923, and not only embodies the objects and 15 advantages as set forth in the Letters Patent aforesaid, but has for its further object to provide an attachment of such class, in a manner as hereinafter set forth, with a pair of pressure exerting elements in the 20 form of segmental plates whereby an increased bearing surface is provided between said elements and the spanner member to provide for a firm seating throughout of said elements against a head to overcome 25 any slack in the latter.

Further objects of the invention are to provide, in a manner as hereinafter set forth, a resonator attachment for banjos and the like for reinforcing the head of the 30 instrument and giving it more life, to act as a strain device for the head for increasing or decreasing the volume of sound at the will of the player, to improve the tone, overcoming slack in the head, simple in construction, 35 and arrangement, strong, durable, thoroughly efficient and convenient in its use, readily installed with respect to the head of the instrument, and comparatively inexpensive to manufacture.

40 With the foregoing and other objects in view, the invention consists of the novel construction, combination and arrangement of parts, as hereinafter more specifically described and illustrated in the accompanying 45 drawings, wherein is shown an embodiment of the invention, but it is to be understood that changes, variations and modifications can be resorted to which come within the scope of the claims hereunto appended.

50 In the drawings wherein like reference characters denote corresponding parts throughout the several views:—

55 Figure 1 is a fragmentary view, in plan, of a banjo showing the adaptation therewith of a resonator attachment in accordance with this invention,

Figure 2 is a top plan view of the spanner member.

Figure 3 is a top plan view of one of the pressure exerting elements. 60

Figure 4 is a longitudinal sectional view of the resonator as applied to the head of the banjo.

The adaptation of the resonator attachment is illustrated by way of example, in 65 connection with a fretted instrument of the banjo type and such instrument comprises a rim 1, over which is stretched a head 2, adjustably secured in position by bracket screws 3. The neck of the instrument is indicated at 4 and which abuts against the outer face of the rim 1. Arranged within the rim 1, as well as extending diametrically thereof, is a dowel or stick 5. The rim 1, neck 4 and dowel 5 are rigidly connected together. 70 The strings of the instrument are indicated at 5', extend over a supporting bridge therefor, as indicated at 6, and are connected to a tail piece 7. The foregoing is the usual construction of instruments of 75 this class and is well understood by those skilled in the art.

A resonator attachment, in accordance with this invention, is interposed between the stick 5 and the inner face of the head 85 2, and said attachment includes a spanner member referred to generally by the reference character 8 and constructed from a thin flat strip of wood, preferably of maple, and which may be varnished, shellacked 90 or finished in any desired manner.

The member 8 consists of a pair of oppositely extending sector-shaped heads 9 and 10 having the outer portion thereof of greater thickness than the inner portion, 95 thereby providing a transverse shoulder 11 on the upper face of the head. The thin portion of each of the heads is indicated at 12, and said heads 9 and 10 are connected together by a rectilinear shaped neck 13. 100 The neck 13 is of the same thickness as the thin portion 12 of each of the heads.

Secured to the upper face of the thin portion 12 of each head, a substantial distance from the shoulder 11, is a transversely extending bridge member 14 of less height than the height of the shoulder 11. Secured to the thin portion 12 of each of the heads, between the bridge member 14 and shoulder 11, is a transversely extending row of 105 spaced aligned headed studs 15, around each of which is threaded portions of the length 110

of a fine wire 16. One end of the wire 16 is fixedly secured to one of the outer studs of each of said rows of studs. The wire 16 extends lengthwise with respect to the member 8 and is mounted on the bridge members 14. The upper face of the thick portion of each of the heads is flat and plane throughout, segmental in contour and provides a large bearing surface for the member 8 when the latter is arranged in operative relation with respect to the pressure exerting elements to be presently referred to.

The inner face of the neck 13 of the member 8, has arranged therein a pair of counter-sunk circular metallic plates 17 of small diameter which provide abutments for a pair of adjusting screws 18 which have threaded engagement with and extend through a circular abutment plate 19, which is mounted upon the dowel or stick 5.

The pressure exerting elements which bear against the head 2 when the attachment is set up in operative position, are indicated generally by the reference characters 20 and 21. Two of these elements are employed and are oppositely disposed with respect to each other. Each of said elements is constructed from a wooden plate, preferably of maple of segmental contour. The upper face of each of said elements is cut away to provide the marginal portion thereof with an up-standing semi-circular rib 22, which bears against the inner face of the head 2 when the element is in operative position.

Each of the pressure exerting elements has secured to its upper face a pair of curved rows of headed studs, and the studs of one row are indicated at 23 and those of the other row at 24. The studs are of less height than the height of the rib 22. Each of the pressure exerting elements is furthermore provided with a length of fine wire 25, having the ends thereof secured to the outer studs of the row of studs 24. The wire 25 is strung across the upper face of the element and connected around the studs 23 and 24. The rib 22 is of substantial width and the upper face thereof, as indicated at 26, is flat and plane throughout.

The oppositely disposed pressure exerting elements are designed to be mounted against the inner face of the head 2 and are so positioned as to avoid extending across the space between the bridge 6 and the tail piece 7, which would otherwise operate to dampen or mute the tone of the instrument instead of increasing the tone volume for which purpose the attachment is intended.

The studs 15, in connection with the bridge members 14, maintain the wire 16 spaced from the upper face of the thin portion of the heads 9 and 10 and also from the neck 13 of the spanner member 8. The studs 23 and 24 are so constructed as to maintain the wire 25 in spaced relation with

respect to the upper face of the pressure exerting elements.

The inner face of each of the pressure exerting elements is flat and plane throughout and provides a large bearing surface for the upper face of the thick portion of each of the heads 9 and 10.

In applying the attachment, the elements 20 and 21 are arranged whereby the upper faces of the ribs 22 will be positioned against the inner face of the head 2 on opposite sides of the plane occupied by the strings 5'. The member 8 is then disposed diametrically with respect to the head 2, so that the upper faces of the thick portions of the heads 9 and 10 will bear against the inner faces of the elements 20 and 21. The member 8 spans the space formed between the pressure exerting elements 20 and 21. When the elements 20 and 21 and member 8 are set up in the manner as stated, the wire carrying faces thereof oppose the inner face of the head 2. The abutment member 19 is then mounted on the dowel or stick 5 and opposes the neck 13 of the member 8. The screws 18 are then adjusted to engage the plate 17 so that the heads 9 and 10 of the member 8 will bear tightly against the inner faces of the elements 20 and 21 and which will cause the ribs 22 to contact throughout their length against the head 2, thereby taking up any slack in the head, as well as to absorb any vibrations thereof. The vibrations imparted to the elements 20 and 21 are transmitted therethrough to the member 8, as well as to the wires 16 and 25, thereby increasing or decreasing the volume of sound.

It is obvious that by tightening or loosening the screws 18, they will operate to force the elements 20 and 21 against the head 2 or to loosen said elements in relation thereto at the will of the operator, thereby increasing or decreasing the volume of sound.

The wire 16 performs the double function of strengthening the tone of the instrument, as well as breaking up echoes in the same manner as acoustic wires in large halls and buildings.

The attachment is capable of being positioned with respect to the instrument, as well as being adjusted independently of the retaining and adjusting elements for the head of the instrument, for intensifying and modifying the tone, as well as acting in the same manner as acoustic wires, that is the breaking up of echoes, and that furthermore the attachment can be secured to and removed from the instrument without altering or in any way changing the parts thereof.

The setting up of the pressure exerting elements in the form of a segmental plate provides large bearing surfaces for the segmental upper faces of the thick portions of the heads 9 and 10, thereby providing for a

firm seating between the spanner member and the pressure exerting elements when pressure is applied to the spanner member and which results in a uniform seating of 5 the ribs 22 against the inner face of the head 2.

It is thought that the many advantages of a resonator attachment, in accordance with this invention, for a fretted instrument, can 10 be readily understood, and although the preferred embodiment of the invention is as illustrated and described, yet changes in the details of construction can be had which will fall within the scope of the invention 15 as claimed.

What I claim is:—

A resonator attachment for the heads of banjos and the like comprising a pair of segmental, pressure exerting plates each 20 having the marginal portion of its upper face provided throughout with an instru-

ment head bearing rib of the same height throughout, a wire strung over and spaced throughout from said upper face of each plate between the rib thereof and further 25 spaced from the head by said rib, a spanner formed with a pair of oppositely extending sector shaped heads each having a segmental outer portion of greater thickness than the inner portion of the head, thereby providing a shoulder intermediate of each head, a wire strung over and spaced throughout from the upper face of the spanner between said shoulders, said outer portions seating 30 against and spacing the wire on the spanner from the lower face of said plates, and means 35 for varying the pressure between the spanner and said plates.

In testimony whereof, I affix my signature hereto.

FRANS R. L. BERGE.
